[57] CLAIM

The ornamental design for an automobile tire, as shown and described.

DESCRIPTION

FIG. 1 is a front view of the automobile tire, showing the new design, each of the rear view, the top plan view and the bottom plan view appearing the same as the front view, it being understood that the tread pattern repeats uniformly throughout the circumference of the tire;

FIG. 2 is a right side view of the automobile tire, the left side view appearing the same as the right side view;

FIG. 3 is an enlarged fragmentary front view, showing in enlargement the portion of 3—3 in FIG. 1; and,

FIG. 4 is an enlarged sectional view, taken on line 4—4 and in the direction of arrows in FIG. 3.
